UNITED STATES PATENT OFFICE

HUGO BORCHARDT, OF BRIDGEPORT, CONNECTICUT, ASSIGNOR TO THE UNION METALLIC CARTRIDGE COMPANY, OF SAME PLACE.

SULLET-PATCHING MACHINE.

SPECIFICATION forming part of Letters Patent No. 258,528, dated May 23, 1882.

Application filed February 10, 1882. (No model.)

To all whom it may concern:

Be it known that I, HUGO BORCHARDT, of Bridgeport, Connecticut, have invented certain Improvements in Bullet Patching Machines, of which the following is a specification.

My improvements relate to that class of bullet-patching machines in which bullets are made to unwrap the lower portions of their bodies with slips of paper by being rolled upon their longitudinal axes across the face of a magazine containing a mass of paper slips of the proper size and shape. A machine for accomplishing this object is shown and described in Letters Patent of the United States No. 159,748, dated February 16, 1875, granted to me for an improvement in bullet-patching machines. In that machine the instrumentality employed to roll the bullets across the curved face of the guard-rail and the face of the magazine is a horizontal rotating disk having a periphery of elastic material.

My present invention embraces the substitution for the elastic periphery of the rotating disk of pairs of elastic rollers contained in recesses formed in the periphery of a rotating disk and mounted on vertical shafts, the bearings of which are affixed to and rotate with the disk. I preferably cause the rollers to rotate positively with sufficient speed to impart to the bullet, which is placed in contact with the two rollers and between them and the concave face of the curved rail, such a speed of rotation as will cause it to draw the patch tight around its body as it rolls across the face of the magazine.

Another feature of my invention consists of a mucilage-distributer, by the operation of which a drop of mucilage taken from a suitable reservoir is deposited upon that part of the patch with which the bullet first acquires contact. The paper slips or patches employed in this class of machines are rhomboidal in shape, with their acute angles slightly rounded. When wrapped around the bullet the portion of the patch extending below the bullet requires to be folded or crimped in upon the base of the bullet. In the machine described in my former patent this object is accomplished by a curved rail arranged in a plane immediately beneath that along which the base of the bul-

let moves, in a position eccentric with reference to the path of the bullet, so that as the bullet is progressively rolled along the projecting lower portion of the patch is gradually crimped in upon the base of the bullet by contact with the curved edge of the crimping-rail. In my former machine the crimping-rail had a smooth curved edge and was stationary. I now provide it with a serrated edge and give it the capacity of yielding outwardly in a horizontal plane, so that if by any accident the bullet drops too far down the crimping-rail will yield to allow the bullet to pass on without stopping the machine. I also make the segment of the guard-rail above the crimping-rail movable by pivoting the segment at one end, thereby allowing a horizontal oscillation for the purpose of allowing convenient access to the crimping-rail, and I make the segment of the guard-rail which adjoins the oscillating segment adjustable in a horizontal plane toward and from the periphery of the patching-machine disk, for the purpose of employing it as a gage, and thereby effecting the discharge in separate places, respectively, of bullets which have been properly patched and of bullets which have accidentally taken up more than one patch, and hence have acquired too great thickness.

The accompanying drawings, representing a bullet-patching machine embodying my improvements, are as follows:

Figure 1 is top view of the machine. Fig. 2 is a vertical section through the line *w w* on Fig. 1 on an enlarged scale. Fig. 3 is a transverse section through the line *x x* on Fig. 2 on an enlarged scale. Fig. 4 is a longitudinal view of a portion of the serrated-edged crimpler on an enlarged scale. Fig. 5 is a top view upon an enlarged scale of the mucilage-distributer and the contiguous portions of the machine. Fig. 6 is a side elevation, partly in section, of the mucilage-distributing arm. Fig. 7 is a vertical section through the line *y y* on Fig. 5 of the cam operating the tail end of the mucilage-distributer; and Fig. 8 is a vertical section through the radial line *z z* on Fig. 1, showing an adjustable gage for effecting the discharge in separate places of bullets properly and improperly patched.

In my improved machine the rotating-disk A is provided with equidistant pairs of rollers

B of elastic material. Each of these rollers is mounted upon the upper end of a vertical shaft, b , extending downward through a bearing, b' , affixed to or forming part of the rotating disk A. The lower projecting end of the vertical shaft b is provided with a pinion, b^2 , which engages a stationary circular rack, b^3 . The rack b^3 is supported by the crooked arms b^4 , affixed to the annular table C. The inner edge of the table C projects slightly under the edge of the rotating disk A for a portion, C' , of its circumference, where the bullets are fed by hand into the spaces between the pairs of rollers and the stationary curved guide-wall c. By the rotation of the disk A the bullets are ultimately brought against the curved face d of the stationary curved rail D, and are thereby slightly compressed against the yielding surfaces of the parallel rollers B. As they are rolled across the face of the rail D they bear against the projecting curved face of the vertically-pivoted plate E, provided with the vertical posts e, in which are the bearings of a horizontal rock-shaft, e' , which carries the mucilage-distributing arm e^2 . As the bullet rolls along the plate E is rocked outward, and, after the passage of the bullet, is returned to its former position by a retracting-spring, E'. There is thus imparted to the plate E, and hence to the arm e^2 , oscillation in a horizontal plane. The arm e^2 also has the capacity of oscillation in a vertical plane by virtue of its support upon the horizontal rock-shaft e' . The oscillation of the rock-shaft e' is effected by the stationary cam F, against which the end of the rock-shaft arm e^3 is held by the expanding spiral spring F', the thrust of which is exerted upon the pin F², inserted through the arm e^2 . The mucilage-distributing arm is provided at its extremity with a finger, e^4 , which, when at rest, bears upon the bottom of the mucilage-reservoir G. When the mucilage-distributer is set into action the finger e^4 has a motion which is induced partly by its connection with the oscillating plate E, which tends to swing it in a horizontal plane, and partly by its connection with the rock-shaft e' , by which it is at first tilted upward as the rock-shaft arm e^3 traverses the downwardly-inclined face f of the cam F. Having been tilted upward sufficiently to clear the wall of the mucilage-reservoir, the finger e^4 swings outward in a horizontal plane as the arm e^3 traverses the short horizontal part f' of the cam F, and is then tilted downward as the arm e^3 , in obedience to the thrust of the spring F', travels up the inclined face f² of the cam F. During the last portion of the oscillatory movement of the plate E the arm e^3 traverses the horizontal face f² of the cam F, and the finger e^4 is thus swung horizontally outward against the face of the outermost patch, H, in the magazine I, and deposits a drop of mucilage near the upper forward edge of the patch, where the bullet first acquires contact with the patch.

It is desirable that the finger, when depositing the drop of mucilage, shall bear upon the

patch with a yielding pressure, and shall have a slight lateral movement to spread the mucilage. This result is accomplished by making the arm e^2 sufficiently slender to have flexibility, or by connecting it with the rock-shaft by means of the hinged joint e^5 , as shown in the drawings, in which latter case, as will be seen, the light spring e^6 exerts a lateral pull, tending to hold the arm e^2 extended, but yields sufficiently to permit the arm e^2 to bend upon the joint e^5 when the finger acquires contact with the patch. The effect of this bending of the arm e^2 is to bring it into a position which is more nearly radial with relation to the vertical axis of oscillation of the plate E, thus increasing the radial distance of the finger e^4 from its vertical axis of oscillation. It hence follows that during the latter part of the outward oscillatory movement of the plate E the finger e^4 moves horizontally a short distance across the face of the outer patch and spreads thereon the drop of mucilage which it has brought from the mucilage-reservoir. As the bullet travels along the oscillating plate E springs back to its normal position, and the described motions of the finger e^4 being thus reversed it is again introduced into the mucilage-reservoir.

After the bullet has been rolled across the face of the magazine I, and has enwrapped its body with a patch, the portion of the patch projecting below the base of the bullet acquires contact with the serrated edge j of the crimping-rail J, held in position by the spring J'. The serrated edge of the crimping-rail is eccentric with relation to the axis of the patching-machine disk, and hence as the bullet rolls along the projecting lower portion of the patch is progressively crimped or folded in upon the base of the bullet by continued contact with crimping-rail.

The portion D' of the guard-rail is made movable by being hung upon the shank of the vertical screw D², in order that it may be swung outward, as shown in Fig. 1, to allow access to the crimping rail, if required. The next adjoining section, D³, of the guard-rail is made adjustable toward and from the periphery of the patching-disk for the purpose of enabling it to act as a gage for the patched bullets.

The distance of the portion K of the concave face of the gage D³ from the patching-machine disk is such as to permit a bullet covered with a single patch to fall from the space between the disk and the portion K of the gage into a suitable receptacle for the patched bullets, which is placed under that portion of the machine. If, however, the bullet has accidentally picked up more than one patch, its increased thickness will cause it to be held by friction between the patching-machine disk and the portion K of the gage, and it will hence be rolled along to the wider space between the portion K' of the gage and the disk, and be dropped at that point into a separate receptacle.

I claim as my invention—

1. In a bullet-patching machine, a concave

- guard-rail, in which is inserted a magazine of patches, in combination with a rotating disk provided with friction-rollers arranged in pairs near the periphery of the disk, and having their axes of rotation parallel with the axis of the disk, for the purpose of preserving the bullets in vertical positions while they are being rolled across the guard-rail and magazine, substantially as set forth.
10. 2. A concave guard-rail, in which is inserted a magazine of patches, and a rotating disk provided with friction-rollers arranged in pairs near the periphery of the disk, and having their axes of rotation parallel with the axis of the disk, in combination with means for effecting the positive rotation of the friction-rollers in directions opposite to the direction of rotation of the rotating disk at a prescribed rate of speed, and thereby imparting to the bullet a 20 slightly more rapid speed of rotation upon its own longitudinal axis than that which would be caused by the progressive rolling of the bullet across the concave face of the guard-rail, for the purpose of causing the bullet to draw 25 the patch tight around its body, substantially as set forth.
3. In combination with bullet-patching mechanism, substantially such as described, a mucilage-reservoir and a mucilage-distributer, 30 consisting of a jointed arm operated as described, and having both a vertical and a horizontal axis of oscillation, for depositing mucilage upon the patches successively at the parts of their surfaces with which the bullets respectively first acquire contact.
35. 4. The oscillating plate E and means for effecting the oscillation thereof upon its vertical axis, and the longitudinal rock-shaft e' , supported upon the oscillating plate E, carrying the mucilage-distributing arm e^2 , and provided with the arm e^3 , in combination with the cam F, for the purpose of imparting to the mucilage-distributing arm e^2 and finger e^4 the resultant motions due to the oscillation of the 40 plate E upon a vertical axis and the oscillation of the rock-shaft e' upon a horizontal axis, substantially as described.
5. In combination with bullet-patching mechanism, substantially such as described, the mucilage-distributing arm e^2 , connected with the 50 rock-shaft e' by the hinged joint e^5 , in combination with the spring e^6 , as and for the purpose set forth.
6. In combination with bullet-patching mechanism, substantially such as described, the oscillating plate E, provided with the retracting-spring E', and having its free end projecting over the space between the guard-rail D and the rotating disk A, provided with the pairs of rollers B, for the purpose of having the oscillation of the plate E effected by the bullets, successively, as they are rolled along the face of the guard-rail.
7. In combination with bullet-patching mechanism, substantially such as described, the 60 crimping-rail J, provided with a spring J', substantially as shown, and for the purpose set forth.
8. In combination with bullet-patching mechanism, substantially such as described, the 70 crimping-rail J, provided with the serrated concave edge j, as shown.
9. In combination with the rotating disk of a bullet-patching machine, substantially such as described, the movable segment D' of the 75 guard-rail, having a range of movement sufficient to carry it out of its operative position, as and for the purpose set forth.
10. In combination with the rotating disk of a bullet-patching machine, substantially such as described, an adjustable gage provided with an offset, and so arranged relatively to the disk that suitably-patched bullets are discharged from the narrower space between the disk and gage, while bullets which have been 80 too thickly patched are held by friction and rolled along and discharged from the wider space between the disk and gage, as set forth.

HUGO BORUHARDT.
